ABSTRACT OF THE DISCLOSURE

In a dye machine, a circular bath is provided and includes at least one drive roll and a constrictive canal portion to circulate the fabric in the circular bath. A pressure control device, a device for circulating a portion of the treating liquor, means for controlling level of the treating liquor, and means for preventing cavitation of the circulating device are attached to the machine.

The present invention relates to dye machines and, more particularly, to multipurpose dye machines for treating fabrics under either high pressure or normal pressure in a dye liquor or a washing and scouring liquor.

The principal object of the present invention is to provide an improved and efficient dye machine suitable for processing fabric under either high or normal pressure by conveying it through a liquid treating bath, wherein a portion of the liquid is circulated by a circulating means so that the textile material is further carried by liquid stream generated by a circulating means and carried by a mechanical means including at least single drive roll.

Another object of the invention is to provide a dye machine provided with a novel pressure control means suitable for processing fabric under a controlled pressure and temperature.

A further object of the invention is to provide a dye machine provided with a level control means for controlling the level of dye liquor in a liquid treating bath during the processing.

A still further object of the invention is to provide a dye machine provided with an improved liquid circulating means without cavitation of the liquid pump, to obtain high working efficiency of the dye machine.

These and other objects and advantages of the present invention will appear more fully in the following specification, claims and drawings wherein:

FIG. 1 is a side elevational view of an embodiment of the dye machine of the present invention, portions being broken away to illustrate various features of the present invention,

FIG. 2A is a side view, partly in section taken along line IIA—IIA, of the level control device shown in FIG. 1,

FIG. 2B is a sectional view, in detail, of the level control device shown in FIG. 2A,

FIG. 2C is a cross sectional view of the level control device taken along line IIC—IIC in FIG. 2B,

FIG. 2D is a cross sectional view of the level control device taken along line IID—IID in FIG. 2B,

FIGS. 3 and 4 are side elevational views of the modified embodiments of the dye machine shown in FIG. 1,

FIG. 5 is a diagrammatic view of the pressure control means for controlling the gas pressure in the closed dye bath of the machine of the invention,

FIG. 6 is a side elevational view of another embodiment of the dye machine provided with a novel means for recycling dye liquor or washing and scouring liquor, according to the present invention,

2

FIG. 7 is a diagram illustrating the relation between the temperature of circulating liquid and the quantity of liquid delivered from the pump.

Generally, the dye machine of the present invention comprises a plurality of unit mechanisms having the same function. Therefore, only the unit mechanism of the dye machine of the present invention is hereinafter explained to simplify the illustration of the invention.

Referring to FIGS. 1, 2A, 2B, 2C and 2D, a typical dye machine of the present invention is shown as comprising a dye bath having a cylindrical outer tank 1 disposed horizontally upon support frames 1a, 1b, and an inside shell 2 horizontally disposed in the outer tank 1.

All interior parts of the tank 1 and the inside shell

2, or parts of the system which come into contact with the corrosive water or dyestuffs, are preferably constructed of stainless steel, similar corrosive resistant metal or corrosive resistant plastic. The inside shell 2 is horizontally disposed in the tank 1 so as to form an approximately circular bath 5 between the inside wall of the tank 1 and the outside wall of the inside shell 2 as shown in FIG. 1. A porthole 4 is positioned at the top portion of the tank 1. The approximately circular bath 5 comprises a starting inclined portion 5a, a narrow canal portion 5b, a bottom portion 5c, an expanded storing portion 5d and a top portion 5e. A drive roll 3 is disposed in the top portion 5e of the circular bath 5, preferably at the boundary between the starting portion 5a and the top portion 5e. A superposed body of gas is contained in the top portion 5e during the operation of the dye machine. A double pair of symmetrical curved plates 6a and 6b are disposed in the narrow canal portion 5b of the space 5 as shown in FIG. 1, so as to form a double constricted canal. At the bottom portion 5c of the space

5, a perforated bottom plate 7 is disposed so as to form a bottom space 8 between the tank 1 and the perforated bottom plate 7. At an upper portion of the inside shell of the expanded portion 5d, an adjusting tank 9 is supported by the inside shell 2, and the adjusting tank 9

is in communication with the expanded portion 5d through a perforated wall 2a of the inside shell 2. Both sides of the inside shell 2 are closed so that an inside reserve tank 2b is formed. Referring to FIGS. 2A, 2B,

2C and 2D, a level control device 10 is connected to the adjusting tank 9 by a lower connecting conduit 10b and further connected to the circular bath 5 by an upper connecting conduit 10c superimposed upon the lower connecting conduit 10b. The level control device 10

comprises an outer cylindrical liquid container 10d and an inner cylinder 10a coaxially secured to the bottom portion of the container 10d.

At the top portion of the cylinder 10d, a vertical rod 10h rotatably engages with a collar 10j affixed to the central top portion of the outer cylindrical liquid container 10d.

The lower portion of the vertical rod 10h is provided with a screw thread which adjustably engages with a mating member 10g rigidly connected to an intermediate cylindrical shell 10e coaxially disposed in the outer cylindrical liquid container 10d in such a way that the lower end of the shell 10e slidably engages with the top end portion of the inner cylinder 10a.

On the other hand, the top end of the intermediate cylindrical shell 10e is provided with a plurality of arms 10f and a boss containing the thread member 10g. Consequently, the space defined by the inner cylinder 10a and the intermediate cylindrical shell 10e can be adjusted by turning the vertical rod 10h.

To turn the vertical rod 10h, a handle 10i is secured to the top end of the vertical rod 10h.

A bottom end of the inner cylinder 10a is connected with a conduit 10k, the bottom end of the conduit 10k opens into the reserve inside tank 2b. Further,

a control valve 11 is positioned in the conduit 10k and

controls the flow therethrough. A discharge conduit 10^l is fluidly connected to the inner cylinder 10^a and a valve 11^a is positioned within the conduit 10^l so as to control the opening and closing of the conduit 10^l. A conduit 12 is connected with the bottom of the tank 1 at a position under the perforated bottom plate 7 and is also connected to a return conduit 16. A conduit 13 is connected with the bottom of the inside reserve tank 2^b and is also connected with the conduit 16. Control valves 14 and 15 are respectively positioned within the conduits 12 and 13 so as to control the liquid stream passing through the respective conduits 12 and 13. The conduit 16 is connected with a circulating pump 21. A conduit 22 is connected at one of its ends to the circular bath 5 at the narrow canal portion 5^b, as shown in FIG. 1, and is connected at its other end to an outlet of the pump 21. The conduit 22 has a portion extending through a heater 23. A control valve 24 is positioned within the conduit 22 so as to control the quantity of the liquid passing through the conduit 22. A discharge conduit 17, controlled by a valve 18, is connected with the conduit 16 and a water supply conduit 19, controlled by a valve 20, is also connected with the conduit 16. The particular connection of the conduit 22 to the narrow canal portion 5^b of the circular bath 5 is selected such that the end of the conduit 22 faces the curved plate 6^a so as to form a jet stream at the constricted canal portions of the curved plates 6^a and 6^b when liquid is supplied from the conduit 22 into the circular bath 5.

A pressure control device 26 is disposed at the top portion of the circular bath 5, preferably the top portion forming the starting inclined portion 5^a of the circular bath 5.

The inside shell of the starting inclined portion 5^a is preferably formed as an inclined plane as shown in FIG. 1.

In the operation of the dye machine shown in FIG. 1, a treating liquor is first supplied into the circular bath 5 through the porthole 4. When the level of the treating liquid in the circular bath exceeds the top level of the adjusting tank 9, the level of the treating liquid is adjusted by turning the handle 10^l of the level control device 10 and the supply of the treating liquid is stopped. Then the pump 21 is driven to circulate a portion of the treating liquid in the tank 1 by way of the circulating means comprising the conduits 12, 16, 22 and the pump 21. In other words, a portion of the treating liquid in the tank 1 is sucked by the pipe 12 and fed into the narrow canal portion 5^b of the circular bath 5 by the pipe 22. During the circulation of the treating liquid, the circulating liquid is heated by the heater 23 so as to maintain the temperature of the treating liquid at the predetermined temperature. When the pump 21 is driven and the circulating liquid is fed into the narrow canal portion 5^b, a jet stream of the treating liquid is formed at the narrow canal portion 5^b, and consequently, the treating liquid flows at high speed to both the bottom portion 5^c and to the expanded storing portion 5^d of the bath 5. One end of a fabric 30 is fed into the circular bath 5 through the porthole 4 and then led to the narrow canal portion 5^b by the rotation of the drive roll 3. When the end of the fabric 30 is fed into the treating liquid, the top end of the fabric 30 is sucked into the narrow canal portion 5^b by the jet stream of the treating liquid and the end of the fabric 30 is then carried to the expanded storing portion 5^d. In the expanded storing portion 5^d of the circular bath 5, the fabric 30 is stocked and finally the top end of the fabric is pushed up to the surface of the treating liquid. Next the driving of the drive roll 3 is stopped and the top end of the fabric is joined to the other end of the fabric to form a closed loop of the fabric. After completion of the preparation for processing, the drive roll 3 is again driven to help circulate the fabric 30. The fabric 30 is always fed into the treating liquid at the starting inclined portion 5^a by the action of the drive roll 3, and

is then sucked into the narrow canal portion 5^b by the jet stream of the treating liquid whereupon it is carried to the bottom portion 5^c and the expanded storing portion 5^d of the bath 5. As mentioned above, the portion of the fabric carried to the expanded storing portion 5^d is continuously pushed upwardly by that portion of the fabric coming from the bottom portion 5^c and consequently the level of treating liquid in the expanded storing portion 5^d becomes higher than the level of the treating liquid in the starting inclined portion 5^a. The level of the treating liquors in the expanded portion 5^d and in the outer liquid container 10^d are maintained at the same level by means of the connection of both portions by way of the adjusting tank 9 and the connecting conduit 10^b and the excessive treating liquor in the expanded storing portion 5^d of the outer liquid container overflows into the intermediate cylindrical shell. Consequently, when the valve 11 is opened, the overflowed liquid is fed into the inside reserve tank 2^b. Therefore, the level of the treating liquor in the circular bath 5 can be always maintained at a constant level.

The quantity of the excessive liquor in the circular bath 5 changes in accordance with the particular mass of the fabric being treated. For instance, if a certain fabric having a large mass is to be dyed by the dye machine of the present invention, such can be accomplished with a good result. In this case, the excessive dye liquor can be reserved in the inside reserve tank 2^b and further is circulated by a circulating means comprising the conduits 13, 16 and 22, pump 21 and heater 23 at any desired setting of the valves 15 and 24. Consequently, any liquor to fabric ratio can be obtained. Further, when the valve 14 is opened, the treating liquor in the inside reserve tank 2^b is circulated together with the treating liquor sucked from the bottom portion 5^c of the circular bath 5 and when the valve 11 is opened, the treating liquid in the expanded storing portion 5^d is fed into the inside reserve tank 2^b through the conduit 10. By controlling the opening of the valves 11 and 15, the circulation speed of the liquid in the bath 5 can be controlled. The fabric carried to the bottom portion 5^c of the bath 5 is smoothly pushed toward the expanded storing portion 5^d without any disturbing eddy current being imparted to the treating liquor in the bottom space 8 by the perforated bottom plate 7, thereby uniform treating can effectively be obtained by using the dye machine of the invention. The drive roll 3 also has the function of spreading the fabric when the fabric 30 is turning over the roll 3. This spreading action of the drive roll 3 contributes in providing the fabric with a better treating action by the treating liquor.

Referring to FIG. 3, a different embodiment of the present invention is shown. A bypass conduit 31 is shown having one end connected with the bottom of the circular bath 5 and the other end connected to the adjusting tank 9. As the liquid pressure at the bottom portion of the circular bath 5 is sufficiently high to carry the treating liquor from the bottom portion of the tank 1 to the top portion of the expanded storing portion 5^d of the bath 5, a portion of the heated liquor jet from the narrow canal portion 5^b is carried to the adjusting tank 9 by the bypass conduit 31. When the valve 11 is closed, the heated liquor carried to the adjusting tank 9 is led to the expanded storing portion 5^d of the circular bath 5, whereby the treating liquor in the expanded storing portion 5^d can be maintained at a better and more uniformly heated condition.

Referring to FIG. 4, another embodiment of the present invention is shown wherein an expanded guide plate 32 is mounted on a starting inclined portion of the inside shell 2 and another drive roll 33 is disposed in the starting inclined portion 5^a of the circular bath 5 in such a way that the drive roll 33 is positioned under the expanded guide plate 32. Therefore, the fabric 30 can be mildly fed into the treating liquor without tension and, consequently, the wet processing of the fabric by the dye

machine shown in FIG. 4 can be mildly performed. Such a modification is particularly in case useful when treating light fabric and helps to prevent any mechanical damage during the processing.

When washing of the fabric treated by the dye machine of the invention is required, the valve 20 is opened to supply fresh water through the water supply conduit 19. The fresh water is fed into the narrow canal portion 5b by the action of the pump 21 and the water is led to the bottom portion 5c of the circular bath 5. The valves 11, 15 and 18 are closed and the valve 11a (FIG. 2A) disposed in the branch conduit 10l is opened, whereby the major portion of the fresh water used for washing the fabric 30 in the circular bath 5 is discharged from the branch conduit 10l, the other and the remaining portion of the fresh water is circulated by the circulating means above-described. Consequently, the washing operation of the treated fabric can be carried out effectively by supplying fresh water in the manner disclosed in the present invention.

It has been found highly desirable to dye synthetic or man made fibers at temperatures elevated above the boiling point of the dye liquor at normal atmospheric pressure. To carry out such a dye operation, it is necessary to maintain the inside pressure of the circular bath at a higher pressure than atmosphere pressure to obtain the desired temperature of the dye liquor. Therefore, the construction of the dye machine must be sufficiently strong to bear the high inside pressure of the tank. However, as the dyeing operation for dyeing synthetic material can be performed at a temperature which is a little higher than the boiling point of the dye liquor for example 100-105° C., if an effective pressure control of the inside pressure of the circular bath can be obtained, very effective and economic dyeing of synthetic material can be achieved. Our improved dye machine is suitable for the above-mentioned purpose.

Referring to FIGS. 1, 3, 4, 5 and 6, an embodiment of the pressure control means of the invention is disclosed. The pressure control means comprises a conduit 35 connected with the tank 1 at the position of the top portion 5e of the circular bath 5, a pressure control device 36 and a safety device 37. The pressure control device 36 comprises a U-shaped conduit 36a connected at its end with the conduit 35. An opened end 36b of the U-shaped conduit 36a faces an opening of a water supply conduit 36c. The opened end 36b and the opening of the water supply conduit 36c are enclosed in a closed box 36d having a discharging aperture 36e. The construction of the safety device 37 is almost the same as that of the pressure control device 36, that is, the safety device 37 comprises a U-shaped conduit 37a connected with the conduit 35 as one body. An opened end 37b of the U-shaped conduit 37a faces an opening of a water supply conduit 37c. The opened end 37b and the opening of the water supply conduit 37c are enclosed in a closed box 37d having a discharging aperture 37e as shown in FIG. 5. Water is continuously fed to the opened ends 36b and 37b from the water supply conduit 36c and 37c, respectively, and the excess water which overflows from the U-shaped conduits 36a and 36b are discharged from the respective apertures 36e and 37e. The effective length of the U-shaped conduit 36a of the pressure control device 36 is shorter than that of the U-shaped conduit 37a of the safety device 37, further, the thickness of the U-shaped conduit 36a is smaller than that of the U-shaped conduit 37a.

The function of the above-mentioned pressure control device is hereinafter described. Supposing the pressure in the top portion 5e of the bath in the tank 1 is P, and the treating liquor is heated to maintain the pressure P and the balanced height of the water in the U-shaped conduit 36a is 1. If the pressure in the top portion 5e of the circular bath 5 exceeds the predetermined pressure

P, the water in the space of the conduit 36a defined by an effective length l is pushed out from the opened end 36b of the conduit 36a, with the attendant result that the gas or air in the circular bath 5 is discharged through the U-shaped conduit 36a. On the contrary, if the pressure in the top portion 5e of the bath 5 in the tank 11 is lower than the predetermined pressure P, the water contained in the conduit 36a is maintained till the pressure of the tank 1 exceeds the level of the predetermined pressure P. The above-mentioned effective length l of the U-shaped conduit 36a can be set to the desired pressure in the tank 1. For example, when the effective length l of the U-shaped conduit 36a is set at 80 cm. and water is fed to the opened end 36b of the conduit 36a, the pressure P in the top portion 5e of the bath 5 can be set at 1.08 kg./cm.² and the liquid temperature in the tank 1 is balanced at 102° C. In other words, when the pressure P exceeds the level of the predetermined pressure P of 1.08 kg./cm.², or the liquid temperature becomes higher than 102° C., the gas in the top portion 5e of the circular bath 5 spouts out through the conduits 35 and 37, consequently the pressure P and the liquid temperature go down whereupon the pressure P and the liquid temperature are again raised by the heating of the dye liquor. The liquid temperature in the tank 1 can thus always be maintained at the desired condition.

The thickness of the U-shaped conduit 37a must be larger than that of the U-shaped conduit 36a so as to prevent trouble caused by insufficient control action of the pressure control device. In other words, if the thickness of the conduit 37a is less than that of the conduit 36a, the quantity of exhaust gas from the U-shaped conduit 37a may be insufficient to lower the inside pressure of the tank 1. However if the thickness of the conduit 37a is sufficiently larger than that of the conduit 36a, when the inside pressure of the circular bath 5 exceeds the level of the predetermined pressure, a quantity of gas sufficient to decrease the inside pressure of the tank 1 can be exhausted through the conduit 37a in a very short time and consequently the liquid temperature can be prevented from exceeding the predetermined level. The adjustment of the working length of the U-shaped conduit 36a can be made by shifting the portion 36b of the conduit in the upward or downward direction and fixing it at the thus set position.

When the dyeing operation is performed at a high temperature above the boiling point of the treating liquor and the treating liquor is circulated by the pumping action of a pump, the phenomenon of cavitation of the pump may disturb the effective circulation of the treating liquor. The above-mentioned drawback can be particularly observed when a centrifugal pump is used. In FIG. 7, an example of the relation between the liquid temperature in ° C. and the quantity of discharging liquid in m.³/min. from the pump 21 is shown. As is clear in FIG. 7, the quantity of discharging liquid remarkably decreases with increase in the liquid temperature, for example, the quantity of discharging liquid at a liquid temperature of 98° C. becomes less than one fourth of that at normal temperature. To eliminate the above-mentioned drawback of the recycling means shown in FIGS. 1, 2, and 3, a cooler 40 may be inserted in the conduit 16 upstream of the pump 21, as shown in FIG. 6. The liquid in the conduit 16 may then be cooled to the desired liquid temperature wherein any troubles due to excessive temperatures are obviated. For example, when the liquid passing in the conduit 16 is cooled to 90° C., the quantity of the discharging liquid from the pump 21 is increased by half over the quantity of the discharging liquid at normal temperature, thus greatly minimizing the possibility of pump cavitation.

The cooled liquid discharged from the pump 21 is then heated by the heater 23 and fed into the tank 1 through the conduit 22. The above-mentioned phenomenon of cavitation can also be eliminated by increasing the liquid

pressure, consequently, the utilization of the cooler 40 must be decided in accordance with whether the liquid pressure in the circular bath 5 of the tank 1 can be increased or not.

Although this invention has been described with respect to a particular embodiment thereof, it is not to be so limited as changes and modifications may be made therein which are within the full intended scope of the invention as defined by the appended claims.

What is claimed is:

1. In a dye machine for treating fabrics moving through a treating liquor such as a dye liquor or washing and scouring liquor, the improvement comprising; a horizontally disposed cylindrical shaped tank forming an outer wall of said dye machine; a closed inside shell horizontally disposed in said tank; a circular bath defined by an inside wall of said tank and an outside wall of said inside shell; means for controlling said treating liquor at a constant level during the operation for treating fabric; means for moving said fabric through said circular bath; circulating means including a circulating pump to circulate a portion of said treating liquor taken from a suction portion of said circular bath to an upper portion of said circular bath; a heater disposed to said circulating means for heating treating liquor discharged from said circulating pump; said circular bath provided with a narrow canal portion.

2. A dye machine of the character described in claim 1, including a pressure control means for controlling the pressure of said superposed body of gas at a constant condition; said pressure control means connected to a top portion of said tank.

3. A dye machine of the character described in claim 1, including means for cooling treating liquor sucked by said circulating pump of said circulating means, said cooling means disposed before said circulating pump.

4. A dye machine of the character described in claim 1, including means for washing fabric treated by said treating liquor by fresh water, said washing means comprising a water supply conduit connected to said circulating means and a liquid discharging conduit connected to said means for controlling the level of said treating liquor.

5. A dye machine of the character described in claim 1, including a bypass conduit connecting a bottom portion of said circular bath with said means for controlling the level of said treating liquor.

6. A dye machine of the character described in claim 1; wherein said circular bath comprising a circular series of several portions arranged as a top portion, a starting inclined portion, said narrow canal portion, a bottom portion and an expanded storing portion for storing temporary the fabric during the treating operation in due order.

7. A dye machine of the character described in claim 1; wherein said suction portion is provided with a perforated plate dividing said suction portion into a passage space for passing fabric and a space connected with said circulating means for circulating a portion of said treating liquor.

8. A dye machine of the character described in claim 6; wherein said narrow canal portion is provided with a double pair of symmetrical curved plates for forming a double constricted canal for carrying said fabric together with said treating liquor.

9. A dye machine of the character described in claim 1; wherein said means for controlling the level of said treating liquor comprising an adjusting tank transversely disposed inside said inside shell at a top portion of said inside shell; a level control device connected to said adjusting tank by a lower connecting conduit and further connected to said circular bath by an upper connecting

conduit superimposed upon said lower connecting conduit; a conduit connecting said level control device with a closed inside space of said inside shell; a conduit connecting said closed inside space of said inside shell with said circulating means; valves for opening or closing both of said conduits; a perforated wall through which said adjusting tank is fluidally connected to said circular bath said upper connecting conduit connecting superposed bodies of gas in said circular bath and said level control device, said lower connecting conduit connecting both treating liquor in said adjusting tank and said level control device; said level control device provided with a mechanism for overflowing an excess treating liquor in said device and a mechanism for adjusting level of said mechanism for overflowing; thereby the level of said treating liquor in said circulating bath can be maintained at a constant level in accordance with adjusting level of said mechanism for overflowing treating liquor in said level control device.

10. A dye machine of the character described in claim 8; wherein said means for moving said fabric comprising a drive roll disposed in said top portion of said circular bath, and said double pair of circular plates.

11. A dye machine of the character described in claim 8; wherein said means for moving said fabric comprising a pair of drive rolls disposed in said top portion and an inclined starting portion of said circular bath and said double pair of curved plates.

12. A dye machine of the character described in claim 1; wherein said circulating means to circulate a portion of said treating liquor comprising a conduit connecting a bottom portion of said circular bath with said circulating pump, and a conduit connecting said circulating pump with said narrow canal portion of said circular bath.

13. A dye machine of the character described in claim 2; wherein said pressure control means comprising a main conduit connected to a top portion of said horizontal cylindrical tank; a safety device connected to an end of said main conduit and a pressure control device connected to said main conduit.

14. A dye machine of the character described in claim 13; wherein said pressure control device comprising a small U-shaped conduit and a small water supply conduit which always pouring water to an open end of said small U-shaped conduit, and a closed box enclosing said small supply conduit and said open end of said small U-shaped conduit, an adjusting device for adjusting level of said open end of said U-shaped conduit, another end of said small U-shaped conduit connected to said main conduit, said closed box provided with an aperture; said safety device comprising a large U-shaped conduit and a large water supply conduit always pouring water to an end of said large U-shaped conduit, and a large closed box enclosing said large water supply conduit and said open end of said large U-shaped conduit connected to said end of main conduit, and said large closed box provided with an aperture.
